UNITED STATES PATENT OFFICE

111,195

DESIGN FOR AN AUTOMOBILE SEAT WARDROBE

Aileen Armour, Los Angeles, Calif.

Application June 3, 1938, Serial No. 77,549

Term of patent 14 years

To all whom it may concern:

Be it known that I, Aileen Armour, a citizen of the United States, residing at Los Angeles, in the county of Los Angeles and State of California, have invented a new, original, and ornamental Design for an Automobile Seat Wardrobe, of which the following is a specification, reference being had to the accompanying drawing, forming a part thereof.

Fig. 2 is a front elevation, showing the doors open.

The present application is a continuation in part of my application, Serial No. D-73,805 filed December 22, 1937.

I claim:

The ornamental design for an automobile seat wardrobe, as shown and described.

AILEEN ARMOUR.
